DRYING MACHINE

Ralph C. Parkes, Glenside, Pa.

Application February 10, 1948, Serial No. 7,392

3 Claims. (Cl. 34—24)

1

My invention relates to the art of drying a material by placing the material in, or moving it through, a drying chamber into which a fluid drying medium, such as heated air, is admitted.

When a material is dried in this manner, the portion thereof which is proximal to the point of admission of the air will be subjected to the full, or maximum drying potential of the air and will, therefore, dry ahead of the distal portions of the material which are subjected to the drying potential remaining after the air has come into contact with and absorbed some moisture from the proximal portions of the material.

For example, if loops of cloth, skeins of yarn, or the like are suspended on poles placed in or propelled through a drying chamber, and if the heated air is caused to flow downwardly through the skeins or loops, the upper portions of the loops, which are acted on by the air while it still possesses its full drying potential, will dry ahead of the lower portions thereof. In addition to the reduced drying potential of the air when it reaches the lower portions of the skeins, it must be remembered that, due to gravity, the lower portions of the loops have a higher moisture content than the upper portions thereof.

This condition can be remedied by turning the loops of cloth or the skeins of yarn, end to end, at some point along their progress through the drying chamber so as to bring the lower portions of the loops or skeins nearer to the point of admission of the heated air.

One object of my invention is to produce improved means for interchanging the positions of the various portions of the materials to be dried so as to subject all portions of the material to the action of the heated air possessing maximum drying potential so as to obtain uniform drying of all portions of the material.

When the poles or other supports on which the loops, skeins or the like are hung, are relatively widely separated while they move through the drying chamber, the problem of causing the skeins or loops to turn end to end, is not a difficult one. But, if the poles referred to are spaced apart sufficiently to permit turning of each successive pole, without the material on such pole getting tangled with the material on adjacent poles, the efficiency of the drying machine is greatly reduced. This is due to the fact that the space available is not fully utilized, and due to the fact that the heated air, following the path of least resistance, will not penetrate the material very much.

To overcome this difficulty, the poles on which

2

the skeins are hung are moved through the drying chamber in relatively close formation thus fully utilizing the available space and compelling the heated air to pass through, instead of along the surface of, the skeins or other material.

It is therefore a further object of the invention to produce an improved method and an improved apparatus whereby the poles may be moved through the drying chamber in close formation and whereby the material on each pole is automatically turned, end to end relative to the pole, at the desired point in the drying chamber, without the material on the pole being turned getting tangled with the material on the preceding or succeeding poles.

During the drying of certain materials it may be desirable to subject the material to some additional treatment such for example, as cooling, humidifying, etc., and it may be preferable to apply such treatment to successive, separate portions of the material.

It is therefore a still further object of the invention to produce an improved method and an improved apparatus whereby the foregoing object may be accomplished.

A still further object of the invention is to accomplish all of the foregoing objects in a single, practical and inexpensive manner.

These and other objects are attained by my invention as set forth in the following specification and as illustrated in the accompanying drawings in which

Fig. 1 is a fragmentary and diagrammatic side elevational view of a drying machine embodying my invention, certain parts being omitted.

Fig. 2 is an enlarged, diagrammatic sectional view on line 2—2 on Fig. 1.

Fig. 3 is an enlarged fragmentary sectional view on line 3—3 on Fig. 2.

Figs. 4, 5 and 6 are fragmentary views illustrating the manner in which a loop of cloth or a skein of yarn is turned end to end.

Fig. 7 is an enlargement of the central portion of Fig. 3.

Figs. 8 to 11 are fragmentary views, partly in section and partly in elevation, showing certain parts which, for clarity of illustration were omitted from the other views.

A machine of the type set forth includes an insulated wall structure 10 defining a drying chamber 12 and suitable brackets 13 for supporting tracks 14 on which rollers 16 are adapted to ride. The rollers 16 and the pivotally joined links 18 form endless conveyors for moving a plurality of supports 20 through the drying chamber 12. The

supports 20 are carried by shafts 21 which extend between the conveyors and are disposed transversely of the path of movement of the conveyors. The supports 20 carry the material to be dried such as loops of cloth or skeins of yarn 22 or the like. The opposite ends of the shafts 21 are suitably mounted in sockets 23 or may be otherwise suitably secured to the conveyors in any well known manner. As shown, the right hand ends of the shafts 21, as viewed in Fig. 1, are inserted into sockets which form part of or are secured to the adjacent conveyor and the left hand sockets which receive the left hand ends of the shafts are secured to, or form part of, a gear 42 which will be hereinafter further described.

The conveyors move from the feed to the delivery end of the machine as indicated by the arrow in Fig. 1 so as to subject the skeins to the action of a drying medium such as heated air which is admitted to the chamber 12 in suitable volume, at suitable temperature and at a suitable velocity. In the embodiment shown the heated air is delivered through nozzles 23 located above the conveyors so that the air must travel downwardly through the chamber 12. The manner in which the air is heated and delivered to the nozzles 23 is conventional and is therefore not shown.

The conveyors on opposite sides of the drying chamber are arranged to travel endlessly over sprocket wheels 28, and 30, which are driven by belts or chain drives 32 which derive from power from any conventional sources of power 34.

The sprocket wheels 28 exert a pushing action on the links of the conveyors and thus cause the links to assume almost vertical positions so that the skein supports 20 move in close formation as shown in the left hand portion of Figs. 1 and 3. This insures penetration of the material by the heated air, and insures maximum utilization of the space in the drying chamber. But, as above stated, the upper portions of the skeins, which are acted on by maximum drying potential the heated air delivered through nozzles 23 will dry well ahead of the lower portions of the skeins which are acted on by the air after it has been partly cooled and partly saturated.

According to my invention, I provide means for turning the skeins, end to end, relative to the nozzles so that the lower, relatively wet, portions of the skeins will be in a position to receive the initial impact of the heated air. To this end, I provide an intermediate pair of sprocket wheels 38 which engage the conveyors at the point in the drying chamber at which it is desired to turn, or change the position of, the skeins.

As the sprockets 38 rotate, in clockwise direction as viewed in Figs. 1, 3 and 7, they exert a pulling action on the conveyor links to their left, and a pushing action on the conveyor links to their right. In this way, as the links carrying a skein support first engage the wheels 38, the links are pulled toward a horizontal position and the support will be spaced from the other succeeding supports as shown at 20A in Fig. 3. Above the conveyors, I provide racks 40 which are adapted to be engaged by gears 42 fixed to the opposite ends of each skein support 20. As the gears are propelled past the racks, they cause their respective skein supports to rotate, in counterclockwise direction, as viewed in Fig. 3. It will be noted that the skein supports 20 are in the nature of relatively flat, and relatively wide blades or bars so that, as they rotate, the free edges 46 of the supports will engage the adjacent portions of the

skeins and cause the skeins to rotate relative to their support.

For example, as the skein supports 20 move toward the sprocket wheels 38, they are closely packed and the sides 48 and 50 of the skein are parallel to the wide sides of the supports, the top portions of the skeins will rest on the supports 20 and the bottom portions of the skeins will be below the lower free edges 46 of the supports 20. As each support arrives below the left hand ends of the racks 40, the support begins to turn in counterclockwise direction, and the edge 46 thereof engages the adjacent vertical side 48 of the skeins carried thereby and transposes them, in the manner shown in Figs. 4 to 6, to the opposite side. The rotation of the support also causes the top portions of the skeins carried by such support to exchange positions with the lower portions thereof. The course of movement of the skeins relative to their supports can be readily visualized by tracing the path of movement of the mark 56 in Figs. 4 to 6.

It will be noted that the sprocket wheels 38, in propelling the skein supports toward the delivery end of the drying chamber, exert a pushing action against the conveyor links so that the skein supports will complete their journey through drying chamber in close formation.

The length of each rack 40, as shown in the drawings, is about equal to the circumference of each gear 42 so that the gears and, hence, the skein supports, will make one complete revolution, as each support moves under the racks. Also, the lengths of the links are related to the lengths of the racks and to the width of the supports 20 so that when each support is moved to position 20A of Fig. 3, it will be sufficiently spaced from the supports to its left and right, to permit turning of the support and the skeins thereon without touching or tangling with a preceding or following support. It is however within the scope of this invention to vary the lengths of the racks, and the links and the width of the supports 20 relative to each other and to the circumference of the engaging gears, as may be desired.

By the method and arrangement described each support, at the selected point during its movement through the drying chamber, is pulled apart from the supports immediately following it and the wet lower portion of the skein is moved to the top of the support while the upper, dry portion of the skein is moved to a position below the skein support. This insures uniform drying of the skeins and, because it permits the skeins to be closely packed while moving in the portions of the drying chamber to the left and to the right of the sprocket wheels 38, the space and the heat input are fully and efficiently used.

It is obvious that the method and structure disclosed are adaptable to the drying of a large variety of articles and that they are also adapted for use in a machine in which the heated air is blown from the sides or from the bottom of the drying chamber. Also, while only one pair of sprocket wheels 38 are shown at about the mid-point of the drying chamber, it is obvious that two or more spaced sets of sprocket wheels 38 can be used so that the skeins may be turned more than once during their progress through the drying chamber.

If it is desired to treat the skeins at position 20A, without turning them, the racks and gears may be omitted and when a particular skein support has been separated from the preceding and following supports, by the action of the sprocket

wheels 38, it is treated or processed, as may be desired. For example, in some cases the material, while traversing position 28A, will be subjected to cold air, moist air, steam, or the like, from suitable nozzles 58 as shown in Fig. 11.

Also, while the skeins are turning, as shown in Figs. 4 to 6, it may be desirable to shield them somewhat from the high velocity drying air emanating from the nozzles 23 so as to guard against the strands of yarn being blown about and tangled. To this end, I provide a shield 60 which is shown in Fig. 11 and which overlies the space in which the skeins are turned.

While, by the structure so far described, the links of the conveyors will assume extended, horizontal positions when pulled by the sprocket wheels and will assume substantially vertical, closely packed, positions when pushed by the sprocket wheels, I prefer to provide positive means for effecting these results so as to insure uniform performance. To this end I provide a chain collapsing device which is shown in Figs. 8 and 9, and a chain extending or spreading device which is shown in Fig. 10, for supplementing the action of the sprocket wheels.

The chain collapsing device shown in Figs. 8 and 9 includes a rocker arm 62 which is pivoted at 63 to ears 64 carried by the frame work of the machine so as to locate the arm 62 above the conveyor. It will of course be understood that a chain collapsing device will be mounted above each conveyor. Each chain collapsing device is provided with a pendent head 66 at one end thereof and a pendent head 68 at the other end thereof. The pendent head 66 is adapted to engage the links of the chains and may be termed the engaging head and the pendent head 68 is adapted to engage the rollers 16 and may be termed the actuating head. In operation, as the head 68 is successively raised by the rollers 16 passing under it the pendent head 66 is successively depressed so as to apply downward pressure against the links. Since the rollers 16 are continuously supported on the tracks while the intermediate links of the chains are not, the downward pressure of the head 66 on the links causes the pivotal connections of the links to move downwardly whereby the links assume the substantially vertical closely spaced formation illustrated.

The pendent head 68 and the portion of the chain collapsing device to the left of pivot point 63 are made heavier than the remaining portion of the device so that when the pendent head 68 is not riding on a roller 16, the pendent head 66 will be elevated out of engagement with the chain links. It will be noted that by this arrangement the motive power for the chain collapsing device is furnished by the movement of the conveyor which causes the spaced rollers 16 to successively come under the pendent head 68 so as to rock the arm 62 about the pivot 63. To facilitate the operation and make the action gradual, the heads 66 and 68 are provided with cam surfaces 69. As will be seen from Figs. 8 and 9 the parts are so arranged and proportioned that as the pendent head 68 approaches its high point, and the head 66 approaches its low point, the pivotal connection of any pair of adjacent links will approach a position below the head 66 so that the main pressure of the head 66 will be exerted in the vicinity of the pivot pins connecting the links.

Each chain extending device of Fig. 10 includes a rocker arm 70 pivoted at 71 to ears 72 carried by the frame of the machine so as to locate the arm 70 above the conveyor. The arm 70 is pro-

vided with a head 74 adapted to engage the links of the chain and the weight of the portion of the arm 70 to the right of the pivot 71 is greater than the remaining portion thereof so that the head 74 is always riding on the links of the chain. The head 74 is tapered downwardly and is provided with a cam surface 75. The function of the head 74 is to apply a drag on the links as they pass successively thereunder to insure that the links assume their extended, horizontal positions.

For this reason, the chain collapsing device is placed near the sprocket wheel or wheels which exert a pushing action on the links, as for example, near the wheels 28, while the chain extending device is arranged to cooperate with the sprocket wheels or wheels 38. Thus, as the sprocket wheel exerts a pushing action against the links, the downward pressure applied by the heads 66 supplements the pushing action of the sprocket wheels 28 and insures collapse of the chain. Likewise, the drag exerted on the chain links by the head 74 supplements the pulling action of the wheels 38 in causing the links to assume their horizontal positions. While I have shown the chain collapsing device only near the sprocket wheels 28, and the chain extending device only near the sprocket wheels 38, it is within the scope of the invention to place these devices wherever their action is needed.

The wide flat pendent bars 20 have their center of gravity so located that, if free to move, they will naturally assume the vertical positions shown in Figs. 1, 2 and 3. Therefore, there is no danger of these bars turning about their axes unless they are positively actuated in the manner described. Also, because they have a relatively narrow transverse section or thickness, they occupy minimum space in the drier.

What I claim is:

1. In the art of drying loops of material in a drying chamber, the method which includes admitting a heated fluid drying medium into said drying chamber, placing said loops on supports with said supports passing through said loops, propelling said supports, in close formation, through a portion of said drying chamber, with a portion of each of said loops relatively near the point at which said fluid medium is admitted into said chamber and with the opposite portion of said loop relatively remote from said point, temporarily separating each support from the preceding and succeeding supports, substantially reversing the position of the loops end to end relative to its said support, while said support is separated to change the relation of the portions of the loops relative to the point of admission of the drying medium, and again propelling said supports, in close formation, through another portion of the drying chamber.

2. A machine for drying loops of material, said machine including a drying chamber, means for admitting a heated fluid drying medium to said chamber, a plurality of supports for said loops, means for propelling said supports, in close formation, through said drying chamber with said supports passing through said loops and with a portion of each loop proximal to, and the opposite portion of said loop distal from, the point of admission of said medium, means intermediate the ends of said chamber for successively, temporarily, spacing each of said supports from preceding and succeeding supports, and means for rotating each of said supports once about its axis while said support is spaced from preceding and

succeeding supports and substantially reversing the positions of said portions of said loops on said support relative to the point of admission of the drying medium.

3. A machine for drying loops of material, said machine including a drying chamber, means for admitting a heated fluid drying medium to said chamber, a plurality of elongated flat bars for supporting said loops, an endless conveyor, means for rotatably connecting said bars to said conveyor, means for propelling said conveyor through said chamber, with said loops depending from said bars, the width of each of said bars being such that the free, lower end of said bar registers with a point on the loop relatively remote from the point of suspension of said loop from said bar, and means intermediate the ends of said chamber for rotating said bars to change the position of said loops relative to said bars.
